(57) **CLAIM**

The ornamental design for a speaker housing, as shown and described.

DESCRIPTION

FIG. 1 is a rear perspective view of a speaker housing showing my new design;

FIG. 2 is a side elevational view thereof, and the opposite side elevational view being the mirror image thereof;

FIG. 3 is a top plan view thereof, and the bottom plan view being the mirror image thereof;

FIG. 4 is a front view thereof; and,

FIG. 5 is a rear view thereof.

The broken line showing on FIGS. 2-3 is for illustrative purposes only and forms no part of the claimed design.
